UNITED STATES PATENT OFFICE.

HARRY SMITH, OF CHICAGO, ILLINOIS, ASSIGNOR TO THE AMERICAN FOUNDRY EQUIPMENT COMPANY, OF NEW YORK, N. Y., A CORPORATION OF OHIO.

SAND CUTTING AND PILING MACHINE.

Application filed November 9, 1921. Serial No. 513,973.

This invention relates to sand cutting machines, and more particularly pertains to novel and useful improvements in electrically propelled and operated machines of this character.

An aim of this invention is to provide an improved construction of sand cutting machine wherein the machine may be electrically propelled and the cutting mechanism 10 may also be electrically operated, and manually adjusted to suit the operating conditions.

Another aim of this invention is to embody in a compact, durable and efficient mechanical organization the features referred to above, and which may be manufactured at low cost and which possesses great flexibility and facilitates the cutting up of a sand pile over which the machine is propelled. 20 The machine involving the improvements of this invention comprises generally a chassis mounted on supporting and steering wheels, which chassis is adapted to be propelled over a surface on which a pile of sand 25 is deposited; a frame pivoted or otherwise mounted on the chassis for angular displacement, and a cutting and piling wheel and motor mounted on said frame as a unit.

The cutting wheel and driving means are 30 mounted as a unit on the frame whereby the adjustment of the cutting wheel at the will of the operator is facilitated; and lost motion is overcome to a large extent.

Other objects and advantages of this invention, together with a more complete understanding of the same will appear from the following detail description and the claims, taken in connection with the accompanying drawings, in which,—

Fig. 1 is a side elevation of a sand cutting machine involving the improvements of my invention;

Fig. 2 is an end view of the same looking from the operator's position; and

Fig. 3 is a plan view of the chassis of the machine.

Referring more particularly to the drawings, 5 indicates generally a chassis, which for the sake of lightness, is constructed of tubing and assumes a form which will be presently described. A frame generally designated F is pivoted on one end of the chassis and carries the cutting element and driving means therefor as a unit.

Referring now in detail to the construc-

tion of the chassis, the same is preferably composed of two pairs of end standards or posts 6 and 7, the posts 6 being connected at their medial portions by a transverse strut 8 and at their upper ends by a similarly arranged bar 9. Swivel brackets 10—10 are mounted on the lower ends of the posts 6 and are bifurcated to receive wheels 11, a handle 12 being carried by and secured to the upper ends of said posts and projecting in a substantially horizontal direction therefrom. The wheels 11 permit the steering of the chassis at the will of the operator.

The other end of the chassis carries driving wheels 13—13, these wheels being 70 mounted between the pairs of posts 7, as best shown in Figs. 2 and 3, and the wheels 13 being substantially in longitudinal alignment with the steering wheels 11—11. The posts 6 and 7 are connected at their upper ends by horizontal bars 14—14, these bars being arranged in divergent pairs so as to provide a rigid structure. Diagonally disposed reinforcing struts 15, 16, 17 and 18 extend from the upper and lower ends of 80 the posts 6 and 7, respectively, and are joined at 19, and the junction of the bars 14, posts 7, and struts 17 comprise bearing members 20 on which the frame F is pivotally mounted.

The frame F carries a cutting element 21, reduction gearing 22 and a source of power for driving the cutting wheel, such as an electric motor 23. The frame is pivoted at 20, and is provided at the inner end with the mast 24 which carries the conductors 25 and control box 26 for the motor 23. The frame in this instance is also provided with a shield 27. The frame is adapted to be tilted manually by means of the screw rod 28 provided with a hand wheel 29 and connected at its inner end to the bifurcated arm 30 rigidly secured to the shaft 31. The sleeve 32 is pivoted to the chassis and the screw rod 28 passes through said sleeve when it is desired to change the angular disposition of the frame F. I also provide sleeve connection 33 for allowing quick movement of the frame when desired.

Referring now to the drive mechanism of 105 this invention, I provide a transverse shaft 34 having a differential casing 35 mounted thereon and containing a conventional form of differential gearing (not shown). The sections of the shaft 34 are mounted in 110

brackets 36 and 37 which brackets are secured to a transverse bar 38 and the shaft 31, as will be best seen in Fig. 3. The free ends of the sections of the shaft 34 carry 5 pinions 38 and 39 which are in mesh with ring gears 40 and 41 fixedly secured to the inner sides of the driving wheels 13—13, these ring gears being secured in place in any suitable manner, such as by means of 10 bolts 42, which bolts encircle the spokes 43 of the driving wheels. It is, of course, to be understood that the ring gears might be secured in any other suitable manner to the driving wheels.

15 The prime mover for the vehicle in this case preferably takes the form of an electric motor 44 mounted near one end of the chassis on a pair of spaced angle bars 45, which angle bars have their respective free ends 20 secured to the transverse bar 38, as at 46, and to the transverse strut 8 as at 47. The motor shaft 48 extends toward the casing 35 and passes into a cylindrical housing 49 formed preferably integrally with said casing 35 and containing a worm 50 for engagement with the worm gear 51 contained in the casing 35, thus forming a worm gear differential drive for the machine.

A control box 52 is mounted to one side 30 of the motor on a pair of metal straps 53 which straps extend between the transverse bar 38 and the strut 8, and are secured to each of the same in a manner similar to the angle bars 45. A switch handle 54 extends 35 from the control box 52 and a similar control box 55 is mounted adjacent the control box 52 so that the speed and direction of rotation of the motor 44 may be changed at will. The conductors from the control box, 40 designated 56, are connected to the motor and to the control box 55 and may also continue to the mast 24. Thus, the operator is enabled to start, stop and reverse the direction of travel of the machine as becomes 45 necessary, and as well to independently control the motor 23 for driving the cutting element.

Thus it will be observed that in the operation the cutting element may be rotated at 50 a desired height above the surface on which a pile of sand is deposited so as to cut the pile of sand and then by a reversal of the direction of rotation of the cutting device the sand may be piled in a heap convenient 55 for further use.

While it is preferred that the construction of frame here shown be employed, any other suitable construction may be substituted, provided that the frame carries the cutting 60 element and the motor for driving the same as a unit.

While a specific construction of this invention has been described, it will be observed that various minor changes in the 65 details thereof may be resorted to where

necessary, and I therefore reserve the right to make such changes as do not depart from the spirit and scope of the invention as claimed.

What I claim is:

1. In a sand cutting machine, in combination, a chassis, supporting and steering wheels therefor, a frame pivotally mounted on one end of said chassis, a cutting element and driving means therefor mounted as a unit on said frame, a prime mover mounted on the chassis and connected with the supporting wheels for propelling the machine, and means on the chassis having a slip connection with said frame for varying the angular disposition of the same. 70

2. In a sand cutting machine, a chassis mounted on wheels, a frame pivoted upon said chassis, sand cutting means carried by said frame, a prime mover for driving said cutting means and also carried by said frame, and means on said chassis for adjusting and locking said frame in relative angular disposition to said chassis, and a slip connection between said adjusting means and said frame. 75

3. In a sand cutting machine, a chassis mounted on wheels, a frame pivoted upon said chassis, sand cutting means carried by said frame, a prime mover for driving said cutting means and also carried by said frame, a substantially horizontal screw mounted on the chassis and connected to the frame for adjusting the angular disposition of the same, and a slip connection between 90 said screw and the frame for permitting movement of the frame independently of the screw. 95

4. In a sand cutting machine, a chassis mounted at one end upon supporting wheels 105 and at the other end upon steering wheels, a frame pivoted at its medial portion upon one end of said chassis, and adapted to overhang one end of the chassis, a cutting wheel horizontally rotatably arranged on the overhanging portion of said frame, a prime mover for driving said wheel mounted on the other end of said frame, reduction gearing mounted on the frame between and operatively connected 110 with the prime mover and cutting wheel, an arm extending from the pivot of said frame, a screw rod pivotally mounted on said chassis and having a one-way slip connection with said arm, and a hand wheel on the free end of said screw rod for manipulating the same for moving said frame about its pivot. 115

5. In a sand cutting machine, a chassis mounted at one end on supporting wheels and at the other end upon steering wheels, 125 a handle mounted on said chassis whereby said machine may be manually controlled, a swinging frame pivotally mounted on said chassis, a horizontally rotatable cutting cylinder carried on said frame, a counterbal- 130

- ancing motor operatively connected for driving said cylinder and mounted at the other end of said frame and means associated with said frame for controlling the angular adjustment thereof.
6. In a sand cutting machine, a chassis mounted at one end on supporting wheels and at the other end upon pivotally mounted steering wheels, a handle mounted on 10 said chassis on said other end whereby said machine may be manually controlled, a swinging frame pivotally mounted on said chassis adjacent said supporting wheels and adapted to overhang said chassis, a horizontally rotatable cutting cylinder carried 15 on the overhanging portion of said frame, a counterbalancing motor operatively connected for driving said cylinder and mounted at the other end of said frame and means 20 associated with said frame for controlling the angular adjustment thereof said means being mounted on said chassis adjacent said steering handle.
7. In a sand cutting machine, a chassis 25 having a pair of driving wheels at one end thereof and a pair of wheels mounted for free rotation about a vertical axis for steering purposes at the other end thereof, a handle at said other end whereby said chassis
- may be guided, a motor mounted on said 30 chassis and operatively connected to said driving wheels, a frame pivotally mounted adjacent said driving wheels, a rotary sand cutting element mounted at one end of said frame and adapted to operate adjacent the 35 surface supporting said machine, a counterbalancing motor mounted at the other end of said frame and operatively connected to said cutting element and means adjacent 40 said handle for manually controlling the angular adjustment of said frame whereby the vertical position of said cutting element may be controlled.
8. In a sand cutting machine, a chassis 45 mounted at one end on supporting wheels and at the other end upon steering wheels, a swinging frame pivotally mounted on said chassis, a horizontally rotatable cutting cylinder carried on said frame, a counterbalancing motor operatively connected for driving 50 said cylinder and mounted at the other end of said frame and means associated with said frame for controlling the angular adjustment thereof.
- In witness whereof, I hereunto subscribe 55 my name this 5th day of October, A. D., 1921.

HARRY SMITH.
